UNITED STATES PATENT OFFICE.

HENRY H. UNZ, OF PHILADELPHIA, PENNSYLVANIA, ASSIGNOR TO THE NATIONAL TYPE WRITER COMPANY, OF PENNSYLVANIA.

TYPE-WRITING MACHINE.

SPECIFICATION forming part of Letters Patent No. 449,640, dated March 31, 1891.

Original application filed May 19, 1887, Serial No. 238,719. Divided and this application filed December 7, 1887. Serial No. 257,250. (No model.)

To all whom it may concern:

Be it known that I, HENRY H. UNZ, of the city and county of Philadelphia, State of Pennsylvania, have invented a new and useful Improvement in Type-Writing Machines, which originally formed a part of an application filed May 19, 1887, Serial No. 238,719, divided by action of the Patent Office November 21, 1887.

10 The improvement hereinafter claimed is described in the following specification and illustrated in the drawings which accompany and form a part of this specification.

15 My invention relates to an improvement in inking-ribbon mechanism for type-writing machines; and it consists, essentially, in operating the inking mechanism from the reciprocating dog-carrying frame of the machine, and in improved means in attaching the ribbon-spool to the machine.

20 In the drawings which accompany and form part of this specification, and in which similar letters denote similar parts, Figure 1 represents front view of rear portion of main frame, showing mechanism for driving the ribbon-spools. Fig. 2 represents front elevation of reciprocating sliding dog-carrying frame. Fig. 3 represents front view of shifting action. Fig. 4 represents side elevation of same. Fig. 25 30 5 represents end view of portion of pawl-driving device, showing friction-pulley. Fig. 6 represents central sectional elevation of a ribbon-spool, shaft, and main frame, showing mechanism for attaching the spool, the shaft, and friction driving-wheel to main frame.

35 A A are the inking-ribbon spools.

C represents the driving-wheels for giving movement to the ribbon-spool.

40 b is the friction driving-shoe of the friction driving-wheel.

B is the spring-actuated drum by which motion is given to the carriage, &c., of the type-writer.

45 e is the shaft upon which the spring-actuated drum revolves.

D represents the reciprocating dog-carrying frame by which the movement of the drum is governed.

50 d is the upper dog, and d' the lower dog, of the reciprocating dog-carrying frame, which

work into the ratchet-wheel d² of the spring-actuated drum.

E represents the anchor (shown in detail, Fig. 3) by means of which either operating-lever F is disengaged from the reciprocating 55 sliding dog-carrying frame. This anchor is supported by the shaft e of the drum.

This shoe b is pivotally connected with the operating-lever F. The lever F is pivoted at f to the main frame, and its end f' rests in a 60 notch f² in the reciprocating dog-carrying frame. The end f⁴ of the lever F has, preferably, a friction-pulley f³, which rests in the notch f². The left-hand lever F is shown with a pawl b' pivoted to it, which pawl works in 65 the ratchet-wheel on the ribbon-spool shaft, (on the left-hand side, Fig. 1,) which device can be used together with or in place of the device shown at the right-hand side of the drawings, Fig. 1.

70 The operation of the reciprocating sliding dog-carrying frame, the dog, and the spring-actuated drum are all described in a certain application filed by me March 14, 1887, Serial No. 230,767.

75 The operation of my improved method of actuating the ribbon-spools is as follows: The levers F are normally engaged with the reciprocating sliding dog-carrying frame, and either of said levers is thrown out of operation by means of the anchor E. When the anchor is moved in the direction of the lever having the friction-shoe, the friction-pulley f³ on end of the lever F is forced out of engagement with the reciprocating frame, and 80 the shoe b is forced up off of the driving-wheel and takes the position shown in dotted lines, Fig. 1, right-hand side. When the anchor is moved in the direction of the lever having the pawl at its end, (left-hand side of Fig. 1,) the pulley f³ on end of the lever F is forced out of engagement with the reciprocating frame, and the pawl b' is forced forward, and the projection b² of said pawl strikes the pin b³ on the main frame, which causes 85 the pawl to turn in its pivoted point and rise up off of the ratchet-wheel. When the frame D reciprocates, according as to which lever is engaged, it causes the corresponding friction driving-shoe to act on its corresponding fric- 90 95 100

tion driving-wheel, thus causing one of the ribbon-spools to revolve, the friction driving-shoe retaining said spool and preventing it from revolving in the opposite direction. A handle e' on the anchor is used for operating the anchor. Ratchet and pawls, as shown in the left side, Fig. 1, may be used in place of the friction-wheel and shoes. If ratchet and pawls be used, an ordinary holding-ratchet 10 may be used as well as the ordinary driving-ratchet, if deemed expedient.

My invention also consists in a novel method for removing the ribbon-spool and shaft upon which it revolves. Fig. 6 shows the 15 mechanism by which I accomplish this result. X is the main frame of the machine. The ribbon-spool and its shaft are attached to the main frame X in the following manner: The shaft G of the ribbon-spool has its inner end 20 made hollow. A projection g on the main frame fits into this hollow end of shaft G. The friction driving-wheel of the ribbon-spool is fixedly attached to the shaft G at the inner end of said shaft G. The shaft G is secured 25 to the projection g by the spring-tooth g', which passes through a hole in the hollow portion of the shaft G and into a detent g² in the projection g. When the spring-tooth g' is elevated, the shaft G, carrying with it the ribbon-spool and friction driving-wheel, may be 30 removed.

In this specification I have shown mechanism whereby the reciprocation of the reciprocating dog-carrying frame causes the ribbon-spools to revolve; but it is obvious that the 35 exact intermediate mechanism may be modified without departing from my invention, it being only necessary that the intermediate mechanism shall be such that when the dog-carrying frame is reciprocated the said movement of the frame will be transmitted to the ribbon-spools, causing them to revolve; but I consider the device shown in this specification as a simple and effective method of 40 accomplishing the result. The device for rendering either of the operating-levers inactive could also be modified without departing from the invention; but I consider the device shown as a simple and effective method of accomplishing the result. The connection between 45 the levers and the frame might be constant and either of the levers rendered inactive by severing the connection between the lever and its corresponding spool.

50 Having now fully described my invention, what I claim, and desire to protect by Letters Patent, is—

1. In combination, a letter-spacing frame, a reciprocating dog-carrying frame operated by said letter-spacing frame, ribbon-spools, and intermediate mechanism, substantially as described, between said reciprocating dog-carrying frame and the ribbon-spool, whereby, when the reciprocating frame is operated, one of the ribbon-spools is revolved. 60

2. In combination, a letter-spacing frame, a reciprocating dog-carrying frame operated by said letter-spacing frame, ribbon-spools, and operating-levers between said ribbon-spools and said reciprocating dog-carrying frame. 65

3. In combination, a letter-spacing frame, a reciprocating dog-carrying frame operated by said letter-spacing frame, ribbon-spools, operating-levers normally engaged in said frame, and means, substantially as described, to render either of said levers inactive. 70

4. In combination, a reciprocating dog-carrying frame, ribbon-spools, friction driving-wheels connected with said ribbon-spools, operating-levers having driving-shoes, and means, substantially as described, to render either of said operating-levers inactive. 75

5. In combination, a reciprocating dog-carrying frame, ribbon-spools, friction driving-wheels connected with said ribbon-spools, operating-levers having driving-shoes and friction-pulleys at their ends, said pulleys being normally engaged with said frame, and means, substantially as described, to disengage either of said levers. 85

6. In combination, a reciprocating dog-carrying-frame, ribbon-spools, operating-levers, and an anchor adapted to render either of said levers inactive. 90

7. In combination, a ribbon-spool, a shaft 95 with which said spool revolves, said shaft having a hollow end, a projection on the main frame which fits in said shaft, and a removable connection between said projection and shaft.

8. In combination, a ribbon-spool, a shaft with which said spool revolves, said shaft having a hollow end, a projection on the main frame which fits in said shaft, and a spring-tooth which passes through the hollow part 105 of said shaft and rests in a detent on the projection. 100
